PALMER & BEARD.

Sleigh.

No. 72,532.

Patented Dec. 24, 1867.

United States Patent Office.

HARVEY D. PALMER AND JAMES H. BEARD, OF LEONIDAS, MICHIGAN.

Letters Patent No. 72,532, dated December 24, 1867.

IMPROVEMENT IN SLEIGH.

The Schedule referred to in these Letters Patent and making part of the same.

TO ALL WHOM IT MAY CONCERN:

Be it known that we, HARVEY D. PALMER and JAMES H. BEARD, of Leonidas, in the county of St. Joseph, in the State of Michigan, have invented a new and improved Method of Winter Land-Conveyance, which may be called a Wheeled Sleigh, or an Adjustable Winter-Vehicle; and we do hereby declare that the following is a full and exact description thereof, reference being had to the accompanying drawings, and to the letters of reference marked thereon.

The nature of our invention consists in attaching to the lower braces which are united with the framework and runners of an ordinary sleigh, a set of wheels, (four,) with arms and levers, so connected that the driver, whenever he approaches a place bare of snow, without getting from his seat, by moving a lever, which is conveniently situated for that purpose, may cause the wheels, (placed inside of and near the runners,) through their connecting-apparatus, to be thrown at once below the runners of the sleigh, ready for rotation.

To enable others skilled in the art to manufacture and use our invention, we will proceed to describe its construction and operation.

Figure 1 is a perspective view of our apparatus.

Figure 2 is a sectional view of the lever K, and its method of attachment to the slotted levers F F; and

Figure 3 represents a top view of the lever K, and the framework with which it is connected. In this figure the sleigh-box is represented as thrown back or removed, for showing more fully the bifurcated bent lever K, aforesaid, which is the actuating-lever, by which (the proper motion being given) the wheeled apparatus, as will be hereafter described, is thrown into and out of operation.

To the frame of an ordinarily-constructed sleigh, A A A A A A A, and runners B B, are secured braces C C C C. These braces (two to each runner) are slotted, as shown at a', so as to receive the ends of the bifurcated arms E E E E, which ends serve as axles (see e' e') upon which the wheels D D D D are rotated inside the runners B B. The arms E E E E, at b' b', are pivoted to levers F F, which are suspended from hangers c' c', secured to the frame of the sleigh. The ends of the levers F F are slotted at d' d', so as to play freely between the jaws of the slotted piece G; the upper end of which is fastened to the actuating-lever K. The actuating-lever K being bifurcated at its base, has each of its forks secured in bearings, I, (see figs. 1 and 2,) which seats or bearings form a part of the pieces H H, figs. 1 and 3, which are fastened to the transverse framework of the sleigh. In fig. 1, the lever K is shown in dotted lines in its normal position, or when the vehicle is designed to be used for travelling on the snow. In fig. 2 its vertical position shows the same adaptation, while the oblique position, in dotted lines, shows it as actuated for throwing the wheels D D D D below the runners B B, for bare ground.

The driver, the lever K being in its vertical position, and wishing to throw the wheels into gear, or below the lower surface of the runners, simply throws the lever K forward, and either holds it with his foot, for a short passage upon wheels, (according to the condition of the road,) or may secure it in any ordinary manner to the inside of the front part of the sleigh-box. The lever K, attached to the piece I, upon being thrown forward, (from the driver,) brings the levers F F, at the slotted ends, upward, and at the opposite ends, where joined to the arms E E E E, downward, thus throwing the wheels D D D D, attached to the arms, below the lower portion of the runners, ready for rotation. When it is desired to go on runners, the lever K is brought back to its vertical position, thus reversing the position of the levers F F, and causing the wheels to be thrown upwards.

It will thus be seen that by a simple and economical apparatus, we have secured to the traveller a sure and independent means of winter land or ice-conveyance, calculated for distant journeys, or a method of passing over bridges or ground when bare of snow, so desirable for transportation of produce of the farm, or productions of the mines or forests.

What we claim as new, and desire to secure by Letters Patent, is—

1. The employment of the wheels, attached to the arms E E E E, and working in the slotted braces C C C C, substantially as shown, for the purposes and uses expressed.
2. The actuating-lever K, connecting-piece G, and slotted levers F F, all as shown for the purposes described.

HARVEY D. PALMER,
JAMES H. BEARD.
